UNITED STATES PATENT OFFICE

2,514,835

MUSIC STRING PITCH REGULATOR

Alfred Bredice, Waterbury, Conn.

Application September 8, 1947, Serial No. 772,656

6 Claims. (Cl. 84—297)

1

This invention relates to pitch regulators, and more particularly to a device for automatically indicating the pitch of a music string.

One object of this invention is to provide a device of the above nature which includes a graduated element which is movable in accordance with the tension of the music string, thereby furnishing a means by which the pitch of the string may be determined.

Another object is to provide a device of the above nature which includes a stem for securing one end of a music string, and a spring which retains said stem and is compressible in varying degrees depending upon the tension of said string.

Another object is to provide a device of the above nature which includes an improved tail piece for securing one end of a music string to an instrument.

Another object is to provide a device of the above nature which is adapted for use upon guitars, mandolins, banjos, violins, pianos, harps, and other stringed instruments.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawings,

Fig. 1 is a perspective view of a guitar having a plurality of the improved pitch regulators installed thereon.

Fig. 2 is a longitudinal sectional view of one of the pitch regulators and a portion of the tail piece of the instrument.

Fig. 3 is a plan view of a plurality of pitch regulators and the tail piece as they would be arranged in a guitar.

Referring now to the drawings in which like reference numerals denote corresponding parts throughout the several views, the letter G indicates a guitar having the usual body 10, neck 11, and keys 12, whereby six strings 13 are secured over a central bridge 14. The lower ends of the strings 13 are attached to a series of the improved pitch regulators R below the bridge 14, the pitch regulators being secured to the body 10 of the instrument by means of a tail piece 15 and a clip 16.

Each of the regulators R comprises a tubular body 17 having a tapped rear end 18 and a curved inwardly-extending flange 19 at its forward end,

2

thereby providing a circular aperture 20 in the forward end of the regulator body. The flange 19 serves as an end abutment for a coiled spring 21 which embraces a slidably stem 22 within the body 10. A circular head 23 at the inner end of the stem 22 serves as an inner abutment for the coil spring 21, and said stem extends outwardly through the aperture 20 and has an angular bore 24 in its outer end. Each of the strings 13 is provided with a ball end anchor 25 whereby the string will be retained in the bore 24 of one of the regulators R.

The rear end of each regulator R is provided with an end rod 26 which has an enlarged threaded head 27 engaged in the tapped end 18 of the body 10. The end rod 26 also has a terminal head 28 and a flat reduced section 29 directly adjacent said head.

If desired, the space between the threaded head 27 and the circular head 23 of the stem 22, may be constructed as a sealed vacuum chamber to provide the resilient force for maintaining the tension of the music string.

The tail piece 15 comprises a tubular cross piece 30 which is oblong in cross section, and a U-shaped anchor member 31 by which the cross piece 30 is connected to the clip 16. The U-shaped member 31 has threaded ends 32 entered through apertures in the cross piece 30 and secured by nuts 33.

In order to hold the regulators R, the cross piece 30 is formed with a series of keyhole slots 34 spaced along its forward portion, each comprising a circular aperture 35 in the top wall of the cross piece 30, and connecting with a narrow slot 36 in the front wall of the cross piece.

Each stem 22 is provided with a series of pitch graduations 37 upon which the edge of the inner flange 19 will serve as an index. The pitch graduations 37 may be arranged and numbered according to any desired system, but preferably are so applied as to provide a scale giving the numerical value of the pitch of the string. One way in which such a scale may be established is to install the regulator R in an instrument of the type in which it is to be used. The string secured thereto will then be tuned, as for example, by comparison with a tuning fork, and a mark and its numerical pitch value applied at the edge of the flange 19, which serves as the index.

This procedure may be repeated as many times as is necessary to establish the desired scale upon the stem 22.

When a plurality of the regulators R are installed in a series, the respective end rods there-

of may be made of different lengths so as to pro-

vide a stepped appearance as shown by the end rods 26, 26a, 26b, 26c, 26d, and 26e, respectively, in Fig. 3.

This stepped arrangement of the regulators R will not influence their function in maintaining the tension of the strings, but will enable the instrument player to more readily locate the desired graduated stem 22 at a glance, whereby rapid tuning of the instrument will be facilitated.

Operation

The improved music string pitch regulator may be applied to any desired stringed musical instrument. If it is to be applied to a guitar, as shown in Fig. 1, the installation may be made originally at the factory, or it may be made as a replacement of the conventional tail piece.

In the latter case, the original tail piece will be removed and the clip 16, to which the tail piece 15 is attached, applied at the lower end of the instrument. The terminal heads 28 of the regulators R may then be slipped into place through the keyhole slots 34, and the strings 13 inserted through the angular bores 24 so as to be retained by the ball ends 25.

The regulator will be adapted for use with strings of different characteristics. Thus, the rod 26 and the threaded head 27 may be rotated in relation to the tubular body 17 to vary the installed position of said body, so as to provide the proper coaction between the string 13, the scale graduations 37, and the regulator body 17.

In order to tune the instrument, the keys 12 will then be manipulated to establish the desired tension in the strings 13. As the tension increases, the graduated stems 22 will be drawn outwardly of the body 10 until the proper pitch is indicated by the flanges 19 which serve as an index for the graduations 37. The instrument will then be in tune.

If one or more of the strings should go out of tune during the course of a musical program, as will frequently happen, it will not be necessary for the player to tune the instrument by the usual method of plucking the strings. It will merely be necessary to adjust each individual string until the proper value is visually indicated upon the respective scale graduations 37.

Thus, one advantage of the instant invention is that the instrument can be visually tuned during the course of a program without disturbing the audience or accompanying players.

Another advantage is that the tuning will be rapid in that the degree of tension will be constantly indicated. Thus, the usual trial-and-error method of tuning will be avoided.

While there has been disclosed in this specification one form in which the invention may be embodied, it is to be understood that this form is shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

Having thus fully described the invention, what is claimed as new, and for which it is desired to secure Letters Patent, is:

1. In a pitch regulator, a body adapted for connection to a musical instrument, a stem adapted for connection to a string of said instrument,

means resiliently connecting said stem to said body, whereby the position of said stem with relation to said body will be determined by the tension in said string, graduations upon said stem, one end of said body serving as an index adjacent said graduations for indicating the tension of said string, said body comprising a tubular member having an inwardly-extending flange at its forward end, said stem being slidably embraced by said flange and having a head at its rear end slidably within said body, and said resilient means comprising a coiled spring embracing said stem and engaged between said head and said flange.

2. In a pitch regulator, a body adapted for connection to a musical instrument, a stem adapted for connection to a string on said instrument, means resiliently connecting said stem to said body, whereby a position of said stem with relation to said body will be determined by the tension in said string, graduations upon said stem, one end of said body serving as an index adjacent said graduations for indicating the tension of said string, the rear end of said body having a tapped bore, and a rod having a threaded head engaged in said bore, said rod being aligned with said stem and having an opposite end head adapted for connection to the musical instrument.

3. In a musical instrument having a string, a pitch regulator comprising a stem secured to said string, an end rod aligned with said stem, and resilient means connecting said stem and said rod; and means securing said pitch regulator to said instrument, said securing means having a keyhole slot, and said end rod having a headed end secured in said slot.

4. The invention as defined in claim 3 in which said regulator comprises a tubular body embracing said stem, and said resilient means, said stem having graduations thereon, whereby tension in said string will draw said stem outwardly of said body until the resistance of said resilient means balances the string tension, and the degree of said tension will be indicated upon said graduations by the end of said body.

5. In a musical instrument having a plurality of strings, a series of pitch regulators, each comprising a stem secured to one of said strings, each of said regulators being provided with an end rod aligned with said stem and having a headed end, and resilient means connecting said stem and said rod; a cross piece having a series of keyhole slots each securing one of said headed ends, and means securing said cross piece to said instrument.

6. The invention as defined in claim 5, in which each of said regulators comprises a tubular body embracing said stem and said resilient means, one of said strings being secured to each stem, whereby the tension of said string will draw said stem outwardly of said body until the tension of said resilient element balances the string tension.
